US0D1013992S

(12) **United States Design Patent** (10) **Patent No.:** **US D1,013,992 S**
(45) **Date of Patent:** **** Feb. 6, 2024**

(54) **SQUEEGEE**

(71) Applicant: **HANSGROHE SE**, Schiltach (DE)

(72) Inventors: **Matthias Oesterle**, Winterbach (DE);
Marco Fläig, Stuttgart (DE)

(73) Assignee: **Hansgrohe SE**, Schiltach (DE)

(**) Term: **15 Years**

(21) Appl. No.: **29/778,652**

(22) Filed: **Apr. 14, 2021**

(30) **Foreign Application Priority Data**

Oct. 14, 2020 (EM) 008203012-0005

(51) **LOC (14) Cl.** **07-05**

(52) **U.S. Cl.**

(57) **CLAIM**

The ornamental design for a squeegee, as shown and described.

DESCRIPTION

FIG. 1 is a perspective view of a squeegee showing our design;

FIG. 2 is a front elevational view;

FIG. 3 is a rear elevational view;

FIG. 4 is a side elevational view;

FIG. 5 is a side elevational view;

FIG. 6 is a top plan view; and,

FIG. 7 is a bottom plan view.

The broken-line disclosures in the drawings represent portions of a squeegee that form no part of the claimed design.

1 Claim, 7 Drawing Sheets
